FLUORESCENT LAMP

Fred Mugnai, Chicago, Ill.

Application August 10, 1953, Serial No. 26,394

Term of patent 14 years

(Cl. D48—20)

To all whom it may concern:

Be it known that I, Fred Mugnai, a citizen of the United States, residing at Chicago, in the county of Cook and State of Illinois, having invented a new, original, and ornamental Design for a Fluorescent Lamp, of which the following is a specification, reference being had to the accompanying drawing, forming a part thereof.

In the drawing:

Fig. 1 is a front perspective view of a fluorescent lamp showing my new design; and

Fig. 2 is a left side elevational view thereof to a smaller scale.

I claim:

The ornamental design for a fluorescent lamp, as shown.
